United States Patent Office

Des. 210,392

Patented Mar. 5, 1968

210,392

DOLL OR SIMILAR ARTICLE

Henrietta Valis, 3508 Mermaid Ave.,
Brooklyn, N.Y. 11224

Filed Dec. 6, 1965, Ser. No. 75

Term of patent 7 years

(Cl. D34—4)

FIG. 1 is a front elevational view of a doll incorporating my new design;

FIG. 2 is a side elevational view thereof;

FIG. 3 is a rear elevational view thereof; and

FIG. 4 is a top plan view thereof.

I claim:

The ornamental design for a doll or similar article, substantially as shown.
